(57) **CLAIM**

The ornamental design for a wire fishing rod holder, as shown and described.

DESCRIPTION

FIG. 1 is a perspective view of a wire fishing rod holder, showing my new design;

FIG. 2 is a front elevational view;

FIG. 3 is a right side elevational view;

FIG. 4 is a left side elevational view;

FIG. 5 is a top plan view;

FIG. 6 is a bottom plan view; and,

FIG. 7 is a rear elevational view thereof.

The broken line showing of environment in the drawings is for illustrative purposes only and forms no part of the claimed design.
